HEEL PLATE

Herman D. Fleschutz, Coudersport, Pa.

Application April 2, 1934, Serial No. 718,732

2 Claims. (Cl. 36—62)

This invention relates to a heel plate designed for use as an ice creeper to prevent the wearer from slipping upon icy surfaces.

Plates of this kind heretofore employed have been objectionable because the ice and snow have packed upon the plates and frozen to them with the result that the spurs or prongs have been rendered inefficient.

An object of the present invention is to provide the heel plate with a means for preventing ice and snow from accumulating thereon so that the spurs or projections are kept clear constantly.

A further object is to provide a heel plate which can be quickly attached to or removed from the shoe of the wearer.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a side elevation of a shoe equipped with the heel plate constituting the present invention.

Figure 2 is a top plan view of the heel plate.

Figure 3 is a bottom plan view thereof.

Figure 4 is a section on line 4—4, Figure 2.

Figure 5 is a plan view of the blanks from which the metal portions of the heel plate are formed, these blanks being shown assembled.

Figure 6 is a section on line 6—6, Figure 2.

Referring to the figures by characters of reference, 1 designates a metal plate of substantially the same configuration and area as the bottom of the heel to which it is to be applied. This plate is formed with angle portions 2 constituting the front corners thereof while additional angle portions 3 are extended from the plate at the rear portions of the sides and at the back thereof as shown in Figure 5. These angular projecting portions are spaced apart and ears 4 extend from the plate between them.

Parallel slots 5 are formed in the plate near the forward portions of its sides and those portions of the plate between the slots and the adjacent side edges are struck upwardly to form raised straps 6. These straps are adapted to overlie slides 7 which rest flat upon the plate and have longitudinal slots 8. The slots receive set screws

9 which are threaded into the plate 1 and, when tightened, will bind the slides upon the plate and hold them against movement. The slides 7 are extended outwardly from the plate to form tongues 10. These tongues are adapted to be bent upwardly at right angles, as shown in Figures 1, 2 and 4. The ears 4 are also adapted to be bent upwardly at right angles while the angular projecting portions 2 and 3 are adapted to be bent downwardly at right angles to form prongs or 10 spurs as shown in Figures 1 and 4.

The plate 1 and the slides 7 are housed within a jacket 11 formed of soft rubber. This jacket extends close to the prongs 2 and 3 and to the ears 4 as shown in Figure 3 and is closed at its 15 sides where it extends between the prongs 3 and the slides 7. Thus all parts of the heel plate except the prongs, ears and tongues are provided with a rubber covering. If desired holes 12 may be formed in the top of the jacket to give convenient access to the screws 9.

The jacket can be applied in any manner desired. For example superposed layers of rubber can be arranged with the plate 1 and the slides 7 between them after which these rubber layers 25 can be vulcanized together at their side edges. Furthermore if preferred the bottom layer of rubber can be vulcanized or affixed directly to the bottom surface of plate 1.

When using the heel plate adjustable straps 13 and 14 can be employed. These are extended over the shoe S and snapped into engagement with the tongues 8 and ears 4. These tongues and ears will bear against the side and rear surfaces of the heel H and when the straps 13 and 14 are 30 tightened the heel plate will be held firmly to the shoe.

By providing the heel plate with a rubber covering or jacket, snow and ice will not pack upon and freeze to the plate. Instead the prongs or spurs 40 2 and 3 will be kept clear at all times so as to act efficiently to prevent slipping. When it is desired to remove the heel plate, as when entering a house or leaving an ice covered surface, it is merely necessary to disengage the straps from the 45 tongues and ears. Snap hooks 15 can be employed for this purpose.

By using adjustable slides 7 it is possible to adjust the tongues 8 toward or from each other so as to fit snugly against the sides of heels of 50 different widths.

What is claimed is:

1. A device of the class described including a plate, a soft rubber jacket thereon, downwardly extended prongs on the plate, ears extending up- 55

wardly from the plate for engagement with the back portion of a heel, slides adjustably connected to the plate, and means detachably connected to the slides and ears for holding the plate in position on the bottom of a heel.

2. A device of the class described including a plate, a soft rubber jacket therefor for preventing snow and ice from freezing to the plate, downwardly extending prongs at the edges of the plate 10 and extending below the jacket, upwardly ex-

tending ears at the edge of the plate for engaging the back portion of a heel, slides mounted on the plate, upwardly extending tongues thereon supported beyond the plate and jacket, said slides being adjustable to position the tongues against the respective sides of a heel, means for fastening the slides against movement, and means detachably engaging the tongues and ears for holding the plate detachably to a heel.
